INVENTOR

BY Victor J. Evans

ATTORNEY

Levi Hayes,
L. B. Middleton
WITNESS:

UNITED STATES PATENT OFFICE.

GEORGE E. HARTSHORNE, OF TULSA, OKLAHOMA, ASSIGNOR OF FORTY-NINE ONE-HUNDREDTHS TO MELVIN C. KIMBALL, OF TULSA, OKLAHOMA.

LICENSE TAG.

Application filed July 29, 1922. Serial No. 578,382.

To all whom it may concern:

Be it known that I, GEORGE E. HARTSHORNE, a citizen of the United States, residing at Tulsa, in the county of Tulsa and State of Oklahoma, have invented new and useful Improvements in License Tags, of which the following is a specification.

This invention relates to improvements in license tags for automobiles and the like, the general object of the invention being to provide means for placing a part on the tag which carries a new date so that the tag can be used for a number of years.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a face view of the invention.

Figure 2 is a rear view of the plate shown in Fig. 1;

Figure 3 an end view of the same; and

Figure 4 a plan view of the plate before attachment.

In these views 1 indicates the license tag which is of the usual construction and contains the holes 2 for attaching the tag to the tag holder of the vehicle. My invention provides an attachment for this tag which consists of a small plate 3 having the characters 4 thereon for indicating the year and the numerals 5 which are the same as the numerals on the tag 1, thus identifying the attachment with the tag. This attaching plate is provided with the holes 6 which will register with some of the holes in the tag 1 so that this attaching plate can be bolted or riveted to the tag 1 in a position where it will cover the numerals of the past year.

This plate is also provided with the tabs 7 which are adapted to be bent over into engagement with the tag. This plate 3 is preferably colored with a different color 50 from that of the plate of the previous year so as to indicate the change. While the drawings show the attachment placed at one end of the tag it will of course be understood that it will be placed in a position to 55 cover the numbers of the previous year so that it will depend on the positions of these numbers as to where the plate is placed.

By this invention it is simply necessary to buy the small attachment plate and place 60 it on the old tag. This will not only save the expense of buying entire new plates but will also save postage in mailing out the tags. This invention also enables the car owner to use the same numbers year after 65 year.

It is thought from the foregoing description that the advantages and novel features of my invention will be readily apparent.

I desire it to be understood that I may 70 make changes in the construction and in the combination and arrangement of the several parts, provided that such changes fall within the scope of the appended claim.

What I claim is:—

As a new article of manufacture, a date plate for use over one end portion of the face of a license tag; the said plate being formed of bendable sheet metal and having a major portion corresponding in length to 80 the width of the license tag and being characterized by end tabs to be bent over the longitudinal edges of the license tag, by a side tab to be bent over the end edge of the license tag, and by an aperture for arrangement in coincidence with an aperture provided in the license tag whereby a common means may be employed for connecting the license tag to an automobile and positively securing the license plate on the license tag. 85 90

In testimony whereof I affix my signature.

GEORGE E. HARTSHORNE.
